UNITED STATES PATENT OFFICE.

CARL A. KELLOGG, OF NEW YORK, N. Y.

FOLDING MECHANISM FOR PRINTING-MACHINES.

1,164,819.

Specification of Letters Patent. Patented Dec. 21, 1915.

Original application filed July 16, 1906, Serial No. 326,411. Divided and this application filed May 23, 1913. Serial No. 769,386.

To all whom it may concern:

Be it known that I, CARL A. KELLOGG, a citizen of the United States, and a resident of the city and State of New York, have invented certain new and useful Improvements in Folding Mechanisms for Printing-Machines, of which the following is a specification.

This invention relates to certain improvements in that class of folding mechanisms which are particularly designed and adapted for use in connection with web printing machines and for severing sheets from the printed web and folding them for presentation to a delivery mechanism, and of which the device shown and claimed in my co-pending patent application Serial No. 326,411, filed July 16, 1906, is a type; and the object of the invention is to provide a mechanism of this general character of a simple and comparatively inexpensive nature and of a compact, strong and durable construction not liable to become deranged or broken during use and capable of operation at high speed, wherein the folding device and actuating means therefor are so constructed and arranged as to avoid interference with the travel of the web or of sheets cut therefrom, and to insure accurate folding of such sheets.

The invention consists in certain novel features of construction, and combinations and arrangements of the several parts of the improved cutting and folding mechanism, whereby certain important advantages are attained, and the mechanism is rendered simpler, less expensive and otherwise better adapted and more convenient for use, all as will be hereinafter fully set forth.

The novel features of the invention will be carefully defined in the claims.

In order that my improvements may be the better understood, I will now proceed to describe the same with reference to the accompanying drawings wherein I have shown one embodiment of the invention, and in which—

Figure 1 is a fragmentary vertical section taken axially through one end of the carrying cylinder of a cutting and folding mechanism constructed in accordance with my invention, the striker blades and their supporting devices being shown in elevation; Fig. 2 is a sectional view taken transversely through the mechanism at one end

of the carrying cylinder, showing the latter together with its companion cutting cylinder and the striker actuating means in elevation; Fig. 3 is a sectional view taken transversely through the carrying cylinder showing the arrangement of the cutting and folding devices; and Fig. 4 is a diagrammatic view illustrating the operation of the folding devices.

As shown in these views, 1 represents the main carrying cylinder of the improved cutting and folding mechanism provided with a peripheral surface whereon the web α is adapted to be received from the printing machine, and having bosses 2, 2 at its opposite ends, said cylinder being keyed or otherwise held upon a shaft 3 passed axially through the open interior of the cylinder with its opposite ends projected beyond the ends or heads thereof and journaled in bearings 4, 4, which may be produced conveniently upon the frame of the printing machine in connection with which the improved cutting and folding mechanism is applied for use.

5 represents a gear wheel upon one end of the shaft 3 whereby movement may be imparted to said shaft for operating the mechanism from any suitable moving part of the printing machine.

6 represents a cutting cylinder arranged at one side of the main carrying cylinder 1 and adapted to cut the web traversing the perimeter thereof, so as to sever the sheets from said web in a well known way, for which purpose said cutting cylinder has a knife 6^a which in the rotation of the parts co-operates with diametrically opposite cutting blocks 6^b, 6^b upon the carrying cylinder so as to penetrate the web α as the same passes between the cylinders 1 and 6. The carrying cylinder is also provided with pins 1^a, 1^a adjacent to the cutting blocks adapted to be thrown out and retracted in a well known way, so as to hold the end of the web to the carrying cylinder after each operation of the knife 6^a, until another sheet is severed therefrom and positioned ready to be operated on by the folding devices.

7, 7 represent folding rolls arranged to receive and fold within their bight the sheets successively severed from the web by the cutting devices; and since in the construction herein shown, each sheet severed

from the web is equal in length to substantially one half the circumference of the carrying cylinder, it will be apparent that for effective operation of the mechanism the 5 folding rolls should be positioned substantially quartering with respect to the cutting cylinder in order that the sheet may be severed by the latter from the web prior to the operation of the folding devices.

10 16 represents an internal gear member which is held stationary upon the frame at one end of the main carrying cylinder with its internal gear surface meshing with the teeth of pinions 11, 11, upon the ends of 15 striker shafts 12, 12, which are extended lengthwise through the cylinder 1 at diametrically opposite sides thereof, and are capable of free rotatory movement due to the engagement of the pinions with the 20 teeth of the internal gear during the rotation of said cylinder 1 of which said rods or shafts 12, 12 partake, by reason of their engagement in bearings which are afforded by radial slots 17, 17 produced in the ends 25 or heads of said main cylinder 1. The internal gear 16 is positioned eccentrically with relation to the rotative axis of the main carrying cylinder 1, and 18 represents a cam also held stationary upon the frame and provided with an eccentric peripheral surface which conforms with the eccentric gear surface of the internal gear 16, and with 30 which are engaged rollers or bearers 19 held upon the rods or shafts 12, 12, the construction and arrangement of the parts being such that throughout the rotatory movement 35 of the cylinder 1, the shafts or rods 12, 12 are continuously rotated about their respective axes while partaking of the rotatory movement of the said cylinder 1 about the shaft 3.

13, 13 represents striker or tucker blades which are secured upon the respective 40 striker or tucker shafts or rods 12, 12, and are adapted, during the rotation of such shafts, to be projected through openings 14, 14 produced at diametrically opposite points in the circumferential wall of said cylinder 1, so as to be operable to insert the sheet carried by the latter within the bight of the folder rolls 7, 7, to be folded, and since said 45 shafts or rods 12, 12 are positioned substantially midway between the cutting blocks 6^a, 6^b, it will be apparent that the strikers, when 50 projected through the openings 14, 14, will be engaged with the middle of the sheet so as to produce a central fold therein.

I have herein shown the carrier provided with two striker shafts and blades, diametrically opposite to each other, and with 55 a peripheral surface whose circumference is equal to twice the length of one of the sheets to be cut from the web and folded, and in practice it is substantially essential to the 60 operativeness of a folding mechanism con-

structed according to my invention that the carrier be provided with two or more striker shafts and blades, and that the circumference of such carrier be equal to the length of a corresponding number of the sheets, 70 since the printed web cannot pass continuously to the periphery of the carrier unless its circumference equals the length of one or more of the sheets, and if its circumference equals the length of a single sheet only, adequate provision cannot be made for the 75 operation of the cutting blade or knife 6^a, and sheet retaining pins 1^a. As the carrier would then have to make a complete revolution before a sheet could be severed and released to the folding rolls and the web would hang loose because freed by both the cutting and retaining means at one and the same time.

By this construction and arrangement of the parts, as in my said co-pending patent 85 application, the shafts or rods 12, 12 wherein the striker blades 13 are carried are continuously and uniformly rotated throughout the turning movement of the carrying cylinder, so that I am enabled to dispense altogether 90 with the employment of cams or like devices for tripping the striker shafts for the projection of the blades, such as have been customarily employed in mechanisms of this general class heretofore in use, and the liability of breakage or derangement of the 95 mechanism due to the shock and stress imposed upon the parts by the operation of such cams being eliminated, I am enabled to operate the improved cutting and folding 100 mechanism at speeds much greater than has heretofore been possible.

The employment of the eccentric internal gear 16 and cam 18, coöperating with the pinions 11, 11 and rollers or bearers 19, 19 105 upon the ends of the respective striker shafts or rods, serves to impart a certain radial thrust to the striker blades 13, 13 when they come into folding position opposite to the rolls 7, 7 so as to insure a more secure insertion of the folded sheet between the rolls, and at the same time this arrangement of the parts permits the folding blades to be completely housed and inclosed within the cylinder throughout the greater part of their 110 travel, so that interference with the web or sheets cut therefrom traversing the perimeter of the cylinder 1 in advance of the folding rolls is absolutely avoided. This is indicated in Fig. 4, where it will be seen 115 that the line *a*, which represents the path traversed by the extremities of the blades 13, 13 is contained within the internal cavity of the cylinder 1 except at the points *b* and *c*, and the striker blade is consequently inclosed within the carrier during two complete and consecutive rotations of its shaft next preceding its arrival in coöperative relation to the folding rolls, so that substantially three-fourths of the perimeter of said 120 cylinder 130

carrier may be traversed by the web, or sheets cut therefrom without liability of being interfered with by the striker blade.

In the structure herein shown, the striker shafts are capable of a certain extent of radial movement toward and from the periphery of the carrier 1, and it will be obvious that during the operation of the mechanism at the high speed which it is possible to attain, centrifugal force is generated sufficient to tend to throw said shafts outward to an excessive extent such as might interfere with the reliable operation of the parts but in the construction shown, this tendency to excessive outward movement of the striker shafts is overcome during the greater portion of the revolution of the carrier 1 by the internal gear 16 which confines the pinions upon the striker shafts and effectually prevents such excessive outward movement, aided by the rollers 19, which bear upon the periphery of the cam 18 oppositely to the internal gear engaged by the pinions. It is understood that, in order to keep the pinions 11 of the striker blade shafts 12 properly in mesh with the internal gear 16, the axes of these pinions and shafts must be maintained at constant distances from the pitch line of the internal gear. As the centers of the cylindric, rotary sheet-carrier and of the downwardly-extended internal gear beyond the end thereof do not coincide, and consequently the circumference of the former is at variance with the pitch line of the latter, it follows that the blade shafts mounted in the carrier could not travel therewith in a true circle and at the same time be kept at the fixed distance required. The shaft-bearings 17 are therefore elongated, that the shafts may have a radial movement alternately inward and outward and thus enable the pinions thereon to move with the pitch line of the internal gear in and out relatively to the carrier's line of rotation. Meanwhile, the cam 18, made to conform in contour with the internal gear 16, causes the rollers 19 traveling around its periphery to act directly and positively upon the shafts 12 and thereby coöperate in discharging the threefold function of keeping the pinions permanently in engagement with the internal gear, controlling the radial thrust of the blade shafts, and counteracting the centrifugal force to which these shafts are subjected.

The improved cutting and folding mechanism constructed according to my invention is of an extremely simple and comparatively inexpensive nature, and is particularly well adapted for use in connection with such printing machines as may be advantageously operated at high speeds, since the stress upon the parts is minimized or equalized in such a manner as to lessen very greatly the liability of breakage or derangement, and the eccentric arrangement of the striker actuat-

ing means operates not merely to insure a more reliable delivery of the sheets to the folding rolls, but also insures against liability of interference of the blades with the sheets during their travel upon the carrier, and it will also be obvious from the above description of my improvements that the mechanism is susceptible of some modification without material departure from the principles and spirit of the invention, as defined in the appended claims, and for this reason I do not desire to be understood as limiting myself to the precise formation and arrangement of the parts as herein set forth in carrying out my invention in practice.

Having thus described my invention, what I claim and desire to secure by Letters Patent is—

1. A mechanism of the character described having a rotary carrier, a plurality of blade shafts mounted upon the carrier and supported for movement toward and from the periphery of the carrier during rotation thereof, folding blades upon the shafts, gears on the shafts, an internal gear eccentrically mounted with respect to the center of rotation of the carrier and meshing with the gears on the blade shafts, a member having a bearing surface fixed with relation to said internal gear, and bearer disks mounted on the blade shafts and traveling upon said bearing surface.

2. A web-folding machine having in combination a rotary carrier having radially slotted ends, blade shafts radially movable in said slots, means for continuously rotating said shafts, bearer disks on said shafts and a fixed cam surface coöperating with said disks to position said shafts.

3. A mechanism of the character described having a rotary carrier, a plurality of blade shafts mounted upon the carrier and supported for movement toward and from the periphery of the carrier during rotation thereof, folding blades upon the shafts, gears on the shafts, an internal gear eccentrically mounted with respect to the center of rotation of the carrier and meshing with the gears on the blade shafts, a bearing surface corresponding in conformation with said internal gear, and bearer disks mounted on the blade shafts and traveling upon said bearing surface.

4. A mechanism of the character described having cutting means, folding rolls, a driven carrier provided with a peripheral surface adapted to receive a web and equal in circumference to the length of a plurality of the sheets severed from such web by the cutting means, and capable of rotatory movement to transport sheets severed from such web by the cutting means to said folding rolls, a plurality of rotatory striker shafts supported upon the carrier, each provided with a striker blade, and capable of move-

ment toward the periphery of the carrier, and adapted, when so moved, to project the striker blade from the carrier in position to fold the sheets between the folding rolls, a fixed cam, rollers on the shafts riding around the cam's periphery, and a single means for imparting rotatory movement to the striker shafts continuously during the rotatory movement of the carrier, including pinions 5 upon the respective striker shafts, and an internal gear meshing with each pinion and positioned eccentrically with respect to the center of rotation of the carrier to permit movement of the striker shaft toward the periphery of said carrier.

5. The combination of cutting means, folding rolls, a driven carrier provided with a peripheral web-receiving surface, and capable of rotatory movement to transport 10 sheets severed from a web by the cutting means to said folding rolls, a rotatory striker shaft supported upon the carrier, provided with a striker blade, and capable of movement toward the periphery of said 15 carrier, and adapted, when so moved, to project the striker blade from the carrier in position to fold sheets between the folding rolls, means operable to rotate the striker shaft continuously during the rotatory movement of the carrier, and a device, co-operating 20 directly with an end of the striker shaft, operable to move the same toward the periphery of the carrier.

6. A folding mechanism comprising cutting means, folding rolls, a driven carrier provided with a peripheral surface to receive a web, a plurality of rotatory shafts supported upon the carrier, each provided with a striker blade and capable of substantially radial movement in said carrier, a single means for moving each of the shafts periodically outwardly to project the striker blades successively from the carrier, and a single means for imparting continuous rotatory movement to all of the shafts during the rotation of the carrier, said latter means being effective to control and limit the outward movement of the shafts whenever said shafts are inwardly removed from their 45 folding-off positions.

7. A folding mechanism comprising cutting means, folding rolls, a driven carrier provided with a peripheral surface to receive a web, a plurality of rotatory shafts 55 supported upon the carrier, each provided with a striker blade and capable of substantially radial movement in said carrier, a single fixed means for moving each of the shafts periodically toward the periphery of the carrier, and a single means for directly imparting continuous rotatory movement to all of the shafts during the rotation of the carrier, said means comprising pinions upon the shafts and a fixed gear positioned eccentrically with respect to the carrier and con-

tinuously meshing with said pinions, said gear and pinions co-operating with said fixed means to determine the radial position of said shafts during substantial portions of each revolution.

8. A folding mechanism comprising cutting means, folding rolls, a driven carrier having a peripheral surface to receive a web, a plurality of rotatory shafts movable in substantially radial slots in the carrier, 75 each provided with a striker blade and movable radially in said carrier, and means for actuating and controlling all of said shafts, said means including a pinion upon each shaft, a fixed internal gear meshing with each pinion and positioned eccentrically with respect to the carrier, a cam conforming in contour with said gear and rollers on said shafts engaging the periphery of said cam.

9. A folding mechanism comprising a rotary carrier, a fixed internal gear adjacent said carrier at one end thereof, a fixed bearing surface adjacent to and conforming in contour with said internal gear, a shaft having a striker blade and journaled in said carrier, a roller on said shaft engaging said bearing surface and a pinion on said shaft adjacent and concentric with said roller and continuously meshing with said internal 90 gear.

10. A mechanism of the character described having, in combination, a driven rotatable carrier provided with a peripheral surface adapted to receive a web, folding 100 rolls coacting with said carrier, cutting mechanism operable upon a web carried by said carrier, said carrier being equal in circumference to the length of a plurality of the sheets severed from such web by the cutting means and being capable of rotatory movement to transport to said folding rolls sheets severed from such web by the cutting means, a plurality of rotatory striker shafts supported upon the carrier and coacting 110 with said folding rolls, said shafts being each provided with a striker blade and being movable toward the periphery of the carrier to project the striker blade from the carrier in position to place the sheets 115 between the folding rolls, and means for continuously and simultaneously rotating said striker shafts during the rotation of the carrier, said means including pinions upon the respective striker shafts and a 120 fixed internal gear meshing with said pinion and positioned eccentrically with respect to the center of rotation of the carrier, thereby permitting intermittent movement of the corresponding striker shaft toward the periphery of said carrier, said means being also operable to retain each striker blade within the periphery of the carrier during its travel past the cutting means.

11. A folding mechanism having cutting 130

means, coacting folding rolls, a driven rotative carrier provided with a peripheral surface adapted to receive a web, equal in circumference to the length of a plurality of the sheets severed from said web by the cutting means, and capable of rotatory movement to transport sheets severed from the web by the cutting means to position for delivery to the folding rolls, a plurality of 10 rotatory striker shafts supported by the carrier, capable of movement toward and from its rotative axis, and provided with striker blades adapted when said shafts are moved outwardly opposite to the folding rolls, to 15 fold off the successive sheets from the carrier between said folding rolls, and means for imparting rotatory movement to the striker shafts continuously and similarly during the rotatory movement of the carrier, including pinions upon the respective 20

striker shafts and an internal gear meshing with each pinion and positioned eccentrically with respect to the rotative axis of the carrier to permit movement of the corresponding striker shaft toward the periphery 25 of the carrier, said means being also operable to retain each striker blade within the carrier during its travel past the cutting means and to project the respective strikers successively from the carrier at the same 30 point in its rotation opposite to said folding rolls to deliver the sheets thereto.

In witness whereof, I have hereunto signed my name in the presence of two subscribing witnesses.

CARL A. KELLOGG.
